(57) **CLAIM**

The ornamental design for a motorcycle wheel with ten spokes, as shown and described.

DESCRIPTION

FIG. 1 is perspective view of an outer side of my motorcycle wheel with ten spokes taken from slightly above and to the left. The reverse or inner side is identical to the outer side; and, FIG. 2 is a cross-sectional view of the wheel of FIG. 1 taken along the lines 2-2 of FIG. 1.
